DESIGN FOR A TWO-FACED DOLL

Kay Perper, Woodside, Long Island, N. Y.

Application December 8, 1943, Serial No. 111,948

Term of patent 3½ years

To all whom it may concern:

Be it known that I, Kay Perper, a citizen of the United States, residing at 35-47 64th Street, Woodside, Long Island, in the county of Queens and State of New York, have invented a new, original, and ornamental Design for a Two-Faced Doll, of which the following is a specification, reference being had to the accompanying drawing, forming part thereof, in which—

Fig. 1 is a front view of the doll awake, showing my new design;

Fig. 2 is a side view; and

Fig. 3 is a rear view of the doll asleep.

I claim:

The ornamental design for a two-faced doll, as shown.

KAY PERPER.
